(57) **CLAIM**

The ornamental design for a testing device, as shown and described.

DESCRIPTION

FIG. 1 is a perspective view of a first embodiment of a testing device in accordance with the present invention.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a cross-sectional elevation view taken along line 8-8 shown in FIG. 6.

FIG. 9 is a perspective view of a second embodiment of a testing device in accordance with the present invention.

FIG. 10 is a front view thereof.

FIG. 11 is a rear view thereof.

FIG. 12 is a right side view thereof.

FIG. 13 is a left side view thereof.

FIG. 14 is a top view thereof; and,

FIG. 15 is a bottom view thereof.

Broken lines illustrate environmental structure and form no part of the claimed design. The dot-dash lines illustrate boundary lines between claimed and unclaimed regions of the testing device and form no part of the claimed design.

1 Claim, 11 Drawing Sheets
